R. GOLDBERG,
CORNER FASTENING FOR METAL BEDSTEADS.
APPLICATION FILED NOV. 8, 1920.

1,382,351.

Patented June 21, 1921.

Inventor
Rubin Goldberg
By his Attorney
Alfred W. Alcorn

UNITED STATES PATENT OFFICE.

RUBIN GOLDBERG, OF BROOKLYN, NEW YORK.

CORNER-FASTENING FOR METAL BEDSTEADS.

1,382,351.

Specification of Letters Patent. Patented June 21, 1921.

Application filed November 3, 1920. Serial No. 422,460.

To all whom it may concern:

Be it known that I, RUBIN GOLDBERG, a subject of the King of Roumania, having filed my papers for citizenship in the United States of America, now residing in the borough of Brooklyn, in the county of Kings, city of New York, in the State of New York, have made certain new and useful Improvements in Corner-Fastenings for Metal Bedsteads; and I do hereby declare the following specification to be a full and clear description thereof, reference being had to the accompanying drawings.

This invention relates to improved devices for readily securing the head and foot pieces of a bedstead to the side pieces thereof, in a rigid manner, the binding mechanism being adapted for combination with a separate corner post.

It also permits of the several connecting parts being readily disconnected from each other and from the corner posts when the bedstead is taken down for packing and removal, so all the parts may be placed in a small space.

In the drawings:

Figure 1 is a top view of the device showing the different parts when locked together;

Fig. 2 is a side elevation of Fig. 1 as indicated by the arrow 2;

Fig. 3 is a view of Fig. 1 on the line of arrow 3;

Fig. 4 is a separate top view of the hollow rectangular fitting part;

Fig. 5 is a side elevation of Fig. 4 on the side next the corner post;

Fig. 6 is a side elevation of Fig. 4 viewed from the side where it connects with the end bar E;

Fig. 7 is an elevation of Fig. 4 viewed from the side which connects with the side bar G, partly broken away;

Fig. 8 is an exterior elevation of Fig. 4 on the side looking toward the end bar E;

Fig. 9 is an angle elevation of the corner post;

Fig. 10, is a side elevation of the tie piece to which the side bar is to be attached, and

Fig. 11 is a detached view of the securing pin.

In my improved device, there are two principal parts, A and B, preferably made of malleable cast iron, which are respectively adapted to be attached by screws or otherwise to the end pieces and sides.

In the drawings, it will be seen that the

part A is constructed in a square formation with a rectangular hollow center space which is surrounded by outer walls a, b, c, and m. On the exterior of one side of the part A, is a wing e extending at right angles from the outer wall c, which enables these two parts to embrace and fit snugly one angle of the corner post C.

The hollow rectangular part A is cast with a holder i, adapted to project into the corner post C, through an opening r, at the corner thereof and is secured in position by the insertion of a tapering pin D. The staple i, has one of its ends terminating in the wing piece e, and the other end in the wall c of the part A.

The outer wall b, of the hollow rectangular body piece A, is pierced with a vertical slot h, which is open at the top and is of the proper width to receive snugly the locking piece B. On the interior of the hollow square of A, is cast a vertical rib g, extending inward, positioned on the wall c, opposite the opening h, which rib will confine the end of B, between it and the wall a, when B is slipped into place. The underside of B, is cut away so as to provide an open slot p, as shown at Fig. 10, which fits over the lower portion of the wall b, of A. The interior face of the wall a, is flush with one side of the vertical slot h, in the wall b, so that when in locked position one side of the end of the tongue of B, lies flat against the interior face of the wall a. The end of the tongue of B will then be confined between the keeping rib g, and the wall a, so it is rigidly braced against any movement of the parts.

I preferably employ a fastening staple i, cast on the outer part of A to make connection with the corner post. In order to obtain a rigid and efficient connection at this point one end of the staple i, terminates in the wall c, and the other end in the angle plate e. The pin D, is curved on one side and right angled on the other side. It is used to hold the part A to the post by being passed into the staple from the top. It will be observed that the pin D, is of tapering formation along its length which will act to firmly wedge the part A to the post when forced down.

The adjoining faces of the wing e, and the wall c, form a right angle on the outside of A which receives and fits snugly the corner of the post C. The staple i, projects through

the transverse slot *r*, made in the corner of the post *C*, into the interior thereof.

In this manner the rectangular corner of *C* and the embracing rectangle formed by 5 the wing *e*, and wall *c*, are brought together so that by inserting and pressing down the pin *D*, a very rigid fastening is obtained between the hollow rectangular section and the corner post.

10 The tongue piece *B* is pierced with holes to receive the fastening screw bolts *s*, *s*, which secure it to the side piece *G*, and the end piece *E*, is secured to the wings *k*, and *l*, by screw bolts *t*.

15 Having thus described my improvements what I claim as new and desire to secure by Letters-Patent is:

In a cast metal corner fastening for metal beds a hollow rectangular body part *A*, hav-

ing four vertical walls, an exterior vertical 20 wing piece *e*, projecting outwardly at right angles from one side of the body part, forming an angle adapted to embrace one corner of a rectangular corner post of a bedstead, a vertical slot opening *h*, in the wall of said hollow body part at the diagonally opposite corner from said wing *e*, said slot opening 25 extending half way down from the top of said body part, a vertical rib *g*, projecting from the interior wall of said hollow rectangular structure positioned at a point opposite said slot opening and means for readily securing the said rectangular body part to one corner of a rectangular bed post and detaching same therefrom, and means for 30 securing said body part to the side of a bedstead, substantially as shown and described.

RUBIN GOLDBERG.
